MOUNTING FOR FRAMES IN BUILDING
WALLS

Daniel T. Downes, Pittsburgh, Pa., assignor to
Pittsburgh Plate Glass Company, Allegheny
County, Pa., a corporation of Pennsylvania

Application October 7, 1938, Serial No. 233,768

6 Claims. (Cl. 72—98)

The present invention relates to means for supporting or securing frames in building walls and notably in walls composed of relatively frangible materials.

5 One object of the invention is to provide mountings of the foregoing type which are adapted to maintain the frames in proper position in the openings in the walls and, yet, which will permit of slight relative movement between the 10 frames and the adjacent portions of the walls.

10 A second object of the invention is to provide means for yieldably supporting the load of the wall above the frame.

In order to obtain a building wall capable of 15 transmitting light and of high thermal insulation value, it has heretofore been proposed to employ hollow blocks or bricks of glass as a building material. Such blocks or bricks were characterized by relatively low coefficients of expansion and contraction with changes of temperature, while the coefficient of metal frameworks is high. Likewise, building walls were subject to settling and deflection by wind. As a result 20 of relative movement between the frames and the portions of the walls adjacent thereto excessive 25 stresses were exerted upon the relatively frangible blocks, thus causing breakage of the latter. If the walls did not contact with the frames, particularly across the lintels, the support afforded 30 the blocks adjacent to the openings was not sufficient to maintain the latter securely in position, and loosening and cracking of the cement might result.

In accordance with the provisions of the present 35 invention the foregoing difficulties are substantially obviated by provision of frames, which comprise outwardly directed flanges providing chases or channels adapted to engage the edges of the openings and including spring elements 40 disposed within the channels adapted resiliently to maintain the frames in proper relationship to the edges of the openings and simultaneously to provide adequate support for the marginal blocks about the openings.

45 For a better understanding of the invention reference may now be had to the accompanying drawings in which Figure 1 is a fragmentary view showing in cross section the construction of a frame and the spring mountings therefor, together with portions of the adjacent wall.

Figure 2 is a fragmentary cross-sectional view taken substantially upon the line II—II of Figure 1 and Figure 3 is a fragmentary cross-sectional view showing upon a larger scale a portion 55 of one of the convolutions of a mounting spring,

together with adjustable means for placing compression thereupon.

In the drawing like numerals refer to like parts throughout.

In accordance with the provisions of the present invention a frame or chase 1 which may be square, rectangular, or any other convenient outline and formed of channel-like sections 8, which may be of iron, steel, aluminum, or any other appropriate material is disposed in an 10 opening 9 in wall 10 composed of blocks 11. The sections shown in Figure 2 comprise a web 12 and marginal flanges 13 adapted to receive the edge portions of the building blocks. The blocks may comprise any convenient material, but as 15 previously stated the invention is particularly applicable to hollow glass blocks of conventional design and which are bonded together by layers 16 of cement.

The frame 1 is resiliently supported within 20 the opening 9 by means of a spring 17 which may comprise a continuous or sectional band or strip of relatively resilient material such as steel or the like. The band preferably is bent to provide a series of almost completely closed 25 loops 18, the vertices of which preferably are substantially flattened in order to provide relatively broad bearing surfaces which alternately contact with a bed or layer 19 of cement, or other appropriate material about the edges of 30 the opening and the web 12. As will be observed in Figure 2 the blocks across the top of the frame may be further supported by means of reinforcing rods or wires 21 embedded in the cementing material. Similar reinforcements 35 may also be provided along the lower edge of the opening and likewise along the sides.

Cover 22 of metal may be laid between layer 19 and the springs in order to prevent the cement, while soft, from flowing between the loops 18 40 and thus impairing operation of the latter. These covers may be in the form of simple straps covering the top portions only or they may include skirts housing the sides of the loops as well as the tops.

In the form of the invention illustrated in Figure 3 the frame 1 and spring 17 are identical with those described, but loops 18 rest upon or engage a plate or bar 25, disposed between the flanges 13 and this bar in turn is supported by 50 set screws 26 which are threaded outwardly through the sections 11 in such manner that by adjustment of the screws the pressure exerted upon the springs or loops 18 may be regulated at will. By means of this construction it is pos- 55

sible to obtain any desired degree (within reasonable limits) of rigidity of the frame in the opening in the wall. Likewise, it is possible so to adjust the springs as to support any appropriate proportion of the load of the wall upon the frame.

The springs may be employed as independent elements which are inserted in the channels of the frame when the latter is assembled in a wall. However, for convenience of handling, they may also be attached, by rivets or clamps, or by welding or soldering or brazing at appropriate spots to the web 12, or to the plate 25 to provide completed assemblies.

15 The springs may extend entirely around the frame or if preferred may be employed merely along one or more sides, for example the top or bottom, as the conditions of loading may require.

20 The mounting springs constituting the subject matter of the present invention admit of relative movement between the frame to compensate for differentials of movement, due to thermal expansion or contraction between the glass blocks 25 and the frame. Likewise, a reasonable degree of settling of movement in the wall is permitted without subjecting the glass blocks to crushing forces. However, the frame is always maintained in proper position within the opening and the 30 blocks above the opening are always adequately supported, thus obviating cracking of the cement between them.

The embodiment of the invention herein disclosed is to be considered merely as exemplary and numerous modifications may be made therein without departing from the invention or the scope of the following claims.

What I claim is:

1. A frame for an opening in a building wall, 40 comprising frame sections having outwardly directed flanges adapted to engage the marginal portions of openings in building walls and a spring comprising a sinuously bent strip of resilient metal disposed between the flanges and 45 running lengthwise of the sections and engaging at the vertices of the situations alternately with the webs between the flanges of the sections, and the marginal portions of the openings resiliently to support the frame.

2. A construction as defined in claim 1 in which the vertices of the situations are flattened to provide extensive bearing surfaces for the spring.

3. A building construction embodying a wall 5 comprising hollow blocks of glass, said wall having an opening formed therein, a frame disposed in the opening, the frame comprising channel sections including webs and outwardly directed marginal flanges and a resilient member disposed 10 between the webs and the adjacent marginal portions of the opening, the resilient member comprising a sinuously bent strip of resilient metal extending lengthwise of the sections and having the vertices of the situations contacting alternately with the webs and said marginal portions.

4. A frame for openings in buildings, comprising a chase, a plate disposed in the chase, resilient elements secured upon the face of the 20 plate and adapted to engage the inner periphery of an opening in a wall and screws threaded through the chase and engaging the plate and being adjustable to vary the distance between the chase and the plate in order to regulate the 25 pressure exerted by the plate upon the resilient elements.

5. A construction as defined in claim 3 in which the vertices of the situations are substantially flattened in order to provide more extensive bearing surfaces at the points of contact with the webs and the marginal portions of the opening.

6. A frame structure for an opening in a building wall, said structure comprising channel sections including a web, outwardly directed marginal flanges, a movable plate disposed between the flanges, screw means threaded through the web for adjusting the plate outwardly, and resilient means upon the plate for engaging the 40 marginal portions of the opening to support the frame resiliently therein, said means comprising a continuous strip of resilient metal bent to provide loops, the vertices of which alternately engage the plate and the adjacent marginal portions of the opening.
